(57) **CLAIM**

The ornamental design for an automobile and/or replica thereof as shown and described.

DESCRIPTION

FIG. 1 is a perspective view of an automobile and/or replica thereof, showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines in the figures show portions of the automobile that form no part of the claimed design, as well as surrounding portions of the automobile that form no part of the claimed design.

1 Claim, 7 Drawing Sheets
